DESIGN FOR A MACARONI OR SIMILAR ARTICLE

Guido Tanzi, Brooklyn, N. Y., assignor to V. La Rosa & Sons, Inc., Brooklyn, N. Y., a corporation of New York

Application May 4, 1934, Serial No. 51,687

Term of patent 7 years

To all whom it may concern:

Be it known that I, GUIDO TANZI, a subject of the King of Italy, and a resident of Brooklyn, in the county of Kings and State of New York, have invented a new, original, and ornamental Design for Macaroni or Similar Article, of which the following is a specification, reference being had to the accompanying drawing, forming part thereof, wherein:—

Fig. 1 is a side elevational view of a macaroni or similar article showing my new design;

Fig. 2 is a similar view looking in the reverse direction, and

Fig. 3 is a view in end elevation of the article of Figs. 1 and 2.

I claim:

The ornamental design for a macaroni or similar article, as shown.

GUIDO TANZI.
